(57) **CLAIM**

The ornamental design for a display screen or portion thereof having a graphical user interface, as shown and described.

DESCRIPTION

The FIGURE is a front view of a display screen or portion thereof having a graphical user interface.

The dot-dashed broken lines depict a boundary of the display screen or portion thereof or a boundary on the display screen and form no part of the claimed design. The dashed broken lines depict portions of the display screen or portion thereof having a graphical user interface which form no part of the claimed design.

1 Claim, 1 Drawing Sheet
